EXTENDED DOOR LATCH

Howard C. Ross, Washington, D. C.

Application April 12, 1948, Serial No. 20,573

3 Claims. (Cl. 70—93)

1

This invention relates to safety locking devices for doors, windows, and the like where it is desired to lock the door or window in a partially open position, and in particular the invention includes a pair of notched bars pivotally mounted on the side of a door or window frame with a lock for securing the bars over a pin or projection on the door or sash.

The purpose of this invention is to provide a door latch somewhat similar to the chain lock whereby a door or window may be locked in different selected adjusted partially open positions and unlocked from either the inside or outside by a key.

With the usual chain lock the door is locked in a predetermined position and the area of the opening is fixed. This type of lock is only adapted to be unlocked from the inside and, therefore, when leaving the house or apartment, it is necessary to completely close the door. With this thought in mind this invention contemplates a latch wherein a lock bolt on a door or window may be locked in notches in bars extending from the frame by a lock on the bars and the lock may be opened by a key.

The object of this invention is, therefore, to provide an improved latch for doors, windows, and the like that may readily be installed on the surface of a door or window, and frame by which a door or sash may be locked in partially open positions and locked and unlocked from either the inside or outside of the door or window.

Another object of the invention is to provide an improved latch for doors, windows, and the like by which a door or window may be secured in a partially open position in which the parts of the latch may be actuated to substantially obscure positions when not in use.

A further object of the invention is to provide an improved latch for locking doors, windows, and the like in different selected partially open positions, which is of a simple and economical construction.

With these and other objects and advantages in view the invention consists of the new and novel combination, construction, and arrangement of parts as hereinafter more fully described, set forth in the claims appended hereto, and disclosed in the accompanying drawings forming part hereof, wherein:

Figure 1 is a sectional plan view illustrating the latch in the position of locking a door in a partially open position.

Figure 2 is a similar view showing the door closed.

2

Figure 3 is a view showing a front elevation of a door in the position illustrated in Figure 1 with parts broken away.

Figure 4 is a sectional view taken on line 4—4 of Figure 1, illustrating the door and latch in elevation.

Figure 5 is a similar view looking toward the edge of a door frame with the door omitted, showing the latch elements open and positioned against the surface of the door frame.

Figure 6 is a vertical section through the mounting base of the latch showing the gear segments on the bars, with parts broken away, and illustrating a modification wherein the base is locked in a channel shaped guide.

Figure 7 is a plan view of the base shown in Figure 6 with the outer ends of the arms broken away.

Figure 8 is a detail showing the lock bolt on the door illustrating a modification wherein the mounting bracket thereof is hinged.

Figure 9 is a view illustrating the latch on a window.

Referring now to the drawings wherein like reference characters denote corresponding parts the improved door lock of this invention includes parallel bars 10 and 11, a mounting base 12, a lock 13, and a lock bolt 14.

The bars 10 and 11 are pivotally mounted in a base 15 on pins 16 and 17, respectively, and the inner edges of the bars are provided with notches 18 and 19 in which the bolt 14 is secured as shown in Figures 3 and 4. The inner ends of the bars are formed with gear segments 20 and 21 and with the teeth of one segment meshing with those of another one bar will move with the other so that it is only necessary to grip one of the bars in opening and closing the latch.

The lock 13 is mounted on the bar 10 and this locks in a section 22 on the bar 11, so that the bars may be locked together over the lock bolt 14 with the bolt held in a pair of notches.

The mounting base 15 is provided with flanges 23 and 24 by which it is secured on the door frame 25 by screws 26 and 27, and the lock bolt 14 is mounted by a bracket 28 on a door 29 by a screw 30.

In the design shown in Figures 6 and 7 bars 31 and 32, similar to the bars 10 and 11, are pivotally mounted in a base 33 on pins 34 and 35, and these bars are provided with gear segments 36 and 37 that also mesh so that one bar will move with the other. In this design the bars are provided with arms 38 and 39 that extend through a slot 40 in the base 33 and into

a slot 41 in a channel-shaped guide 42, wherein the base 33 with the arms and bars 31 and 32 is locked in the guide when the bars are extended outwardly in the position of locking the lock bolt 14, whereas with the bars 31 and 32 opened, as illustrated in Figure 5, the arms 38 and 39 will be free of the notch or slot 41 so that the base 33 may be slid out of the guide 42. By this means the guide 42 may be mounted upon the door or window frame by the screws 43 and 44 and when the base 33 is inserted the screws will be covered so that the latch may not be removed by a screw driver, when the door or window is locked. In this design the bar 31 is provided with a lock 45 which is mounted thereon by rivets 46 and 47, and a corresponding lock section 48 with a tongue 49 is mounted on the bar 32 by rivets 50 and 51.

In the design shown in Figure 8 a lock bolt 52, similar to the bolt 14 is carried by a hinged bracket 53 so that it may be moved to the position shown in dotted lines when not in use.

In the illustration shown in Figure 9 the latch is mounted on a window with a base 33 mounted on the sill 54, and the bars 31 and 32 locked over a bolt 55 on a sash 56, and it will be understood that the latch may be used on a window, door, or the like, and located in any suitable position thereon.

When not in use the bars may be opened to positions against the surface of the frame, as shown in Figure 5, so that the parts are substantially out of the way.

With the parts arranged in this manner a door or window may be locked in different selected partially open positions, and particularly, when used on a door, the door may be unlocked from either the inside or outside. The bolt 14 on the door is positioned in one of the pairs of notches in the bars and the outer end of the bolt may be provided with a head 57 to prevent its being forced through the notches.

What is claimed is:

It will be understood that modifications may be made in the design or arrangement of the parts without departing from the spirit of the invention.

1. In a latch for locking a door in a partly open position, the combination which comprises a bracket adapted to be attached to a door frame, a pair of bars having gear segments on one of the ends thereof and notches in the meeting edges, means pivotally mounting the bars on the bracket with the gear segments positioned to mesh and with the notches in the meeting edges of the bars positioned in registering relation, a bolt having a mounting bracket on one end, said bracket of the bolt adapted to be attached to a door of the said door frame with the bolt posi-

tioned to selectively extend through the said notches in the meeting edges of the bars, and means locking the bars together.

5 2. In a latch for locking a door in a partly open position, the combination which comprises a bracket adapted to be attached to a door frame, a pair of bars having gear segments on one of the ends thereof and notches in the meeting edges, means pivotally mounting the bars in the bracket with the gear segments positioned to mesh and with the notches in the meeting edges of the bars positioned in registering relation, a bolt having a mounting bracket on one end, said bracket of the bolt adapted to be attached to a door of the said door frame with the bolt positioned to selectively extend through the said notches in the meeting edges of the bars, a lock bolt positioned on one of the bars and a key actuated lock mounted on the other bar and positioned to coact with the lock bolt for securing the bars with the meeting edges thereof together.

20 3. In a latch for locking a door in a partly open position, the combination which comprises a guide adapted to be attached to a door frame, a bracket slidably mounted in the guide, a pair of bars having gear segments on one of the ends thereof and notches in the meeting edges, means pivotally mounting the bars in the bracket with the gear segments positioned to mesh and with the notches in the meeting edges of the bars positioned in registering relation, arms extended from the ends of bars on which the gear segments are positioned and positioned to extend through the bracket and into the guide for retaining the bracket in the guide with the bars extended whereby the meeting edges thereof are together, a bolt having a mounting bracket on one end, said bracket of the bolt adapted to be attached to a door of the said door frame with the bolt positioned to selectively extend through the said notches in the meeting edges of the bars, and means locking the bars together.

45 HOWARD C. ROSS.
